WELL CASING

Clausey L. Dailey, Meadville, Pa.

Application December 2, 1938, Serial No. 243,638

3 Claims. (Cl. 285—22)

This invention relates to well casings and more particularly to an improved casing head and drop pipe supporting means.

An object of this invention is to provide an improved means for supporting a drop pipe in a casing head so as to prevent surface water or other material from entering the casing.

Another object of this invention is to provide an improved drop pipe supporting means in combination with a casing head which is so constructed that the supporting means for the drop pipe may be adjusted relative to the casing head in order to accommodate the drop pipe where the well is not straight as is usually the case.

Another object of this invention is to provide a device of this kind which can be mounted on the present well casing and which will eliminate the use of the conventional stuffing box and will seal the drop pipe relative to the well casing so as to exclude both surface water and other external pollution of the well.

The device herein disclosed has been designed particularly for use in wells for water but may also be used for other types of wells where an inner pipe is inserted within the well casing and supported from the casing head.

To the foregoing objects and to others which may hereinafter appear, the invention consists of the novel construction, combination and arrangement of parts as will be more specifically referred to and illustrated in the accompanying drawings, wherein is shown an embodiment of this invention, but it is to be understood that changes, variations and modifications may be resorted to which fall within the scope of the invention as claimed.

In the drawings:

Figure 1 is a detail side elevation of a casing head and drop pipe supporting means constructed according to this invention mounted on a well casing and a drop pipe.

Figure 2 is a detail top plan of the device.

Figure 3 is a longitudinal section taken on the line 3—3 of Figure 2.

Figure 4 is a sectional view taken on the line 4—4 of Figure 1.

Figure 5 is a sectional view similar to Figure 3 but showing the drop pipe eccentric to the well casing.

Figure 6 is a sectional view taken on the line 6—6 of Figure 5, and

Figure 7 is a sectional view taken on the line 7—7 of Figure 5.

Referring to the drawings the numeral 10 designates a well casing and the numeral 11 designates generally a drop pipe which is inserted in the well casing 10 and has a diameter substantially smaller than the diameter of the casing 10.

In the drilling of the wells in the majority of cases, the wells are not drilled in a true vertical line, this being due to the conditions of the earth's strata which cause the drill rod to be shifted out of plumb. When it is desired to insert a drop pipe in the well casing 10 and have the drop pipe 11 vertical, it is necessary to provide a means 10 which may be shifted relative to the casing 10 in order to properly support the pipe 11 in its eccentric position relative to the casing 10.

The casing 10 at its upper end is provided with a casing head 12 having a cylindrical body 13 snugly engaging about the pipe 10. The body 13 at its upper portion is provided with an enlarged portion 14 having an annular seal receiving recess 15 therein. The body 12 at its upper portion is provided with diametrically opposed 20 ears 16, the purpose for which will be hereinafter described. The casing 10 is sealed relative to the head 12 by means of a sealing member 17 which may take the form of lead or like sealing means which may be poured into the seat 15 and then 25 otherwise caulked or tightened in the seat 15 so that the head 12 will be properly sealed in the upper end of the casing 10. A cover plate 18 is adapted to engage the upper end of the head 10 and is provided at substantially the center there- 30 of with an opening 19 therethrough which is only slightly smaller than the inner diameter of the casing 10. The cover 18 is provided with dia- 35 metrically opposed ears 20 adapted to overlie the ears 16 and bolts 21 engage through the ears 35 20 and 16 so as to hold the cover or plate 18 in position on the upper end of the head 12.

In order to provide a means whereby the drop pipe 11 may be supported relative to the casing 10, I have provided a pair of clamping members 40 22 and 23 which are semi-cylindrical in configuration and are adapted to engage about the pipe 11 adjacent the head 12. The clamping members 22 and 23 are provided adjacent the upper end portions thereof with laterally projecting ears 45 24 and 25 respectively which are bolted together as by bolts 26. The inner end portions of the clamping members 22 and 23 are also provided with ears 27 and 28 respectively and bolts 29 hold the ears 27 and 28 in clamping position. 50

The inner end portions of the clamping members 22 and 23 are provided with base flanges 30 and 31 respectively and the base flange 30 is pro- 55 vided with a laterally projecting lug or ear 32. The flange 31 is provided with a laterally pro-

jecting lug or ear 33 and when the correct position of the drop pipe 11 has been determined the cover 18 is drilled and the holes tapped and bolts or screws 34 and 35 are then extended through the ears 32 and 33 and threaded into the cover 18. When the bolts 34 and 35 are tightened a gasket 36 is interposed between the inner ends of the clamping members 22 and 23 and the cover plate 18 so that tightening of the bolts 34 and 35 will seal the inner end of the drop pipe supporting member on the cover 18.

In Figures 5, 6 and 7 the drop pipe 11 has been shown as being eccentric to the casing 10. At the time the correct position of the pipe 11 has been determined, the cover 18 is drilled and the holes therein threaded thereafter pipe 11 will be tightly held in its correct position relative to the casing 10. The gasket 36 will prevent external water or material from entering the interior of the casing 10 so that the water and other liquid withdrawn from the well will not be polluted.

In the use of this device, the casing head 12 is initially positioned at the upper end of the casing 10, the bore of the head 12 being such as to snugly receive the casing 10. The sealing means 17 is then inserted in the seat 15 of the head 12. The cover 18 may then be applied to the head 12 and the drop pipe 11 then inserted through the opening 19 in the cover 18. Where the casing 10 is plumb the drop pipe 11 may take a position coaxial with the axis of the casing 10 as shown in Figure 3. However, where the casing 10 is out of plumb and this is the case with the majority of wells, the drop pipe 11 may take the position shown in Figure 5 where the pipe 11 is eccentric to the casing 10. The drop pipe supporting member comprising the two clamping members 22 and 23 are then engaged about the pipe 11 above the head 12 and a sealing member 37 may be placed in a recess 38 provided in the drop pipe supporting member comprising the two clamping members 22 and 23. The sealing member 37 may be in the form of lead or any other suitable sealing means. The gasket 36 is inserted between the drop pipe supporting member and the cover 18 and where the casing 10 is out of plumb as indicated in Figure 5 the drop pipe 11 will be positioned eccentric to the casing 10.

When the correct position of the drop pipe 11 has been determined, the cover 18 is then drilled and the bolts 34 and 35 are then inserted in the threaded holes and the supporting member 22-23 is tightened onto the cover 18. This drop pipe supporting means has been placed in practical use and has been found to be more satisfactory than conventional gland devices, this being due to the fact that the conventional gland devices do not permit the drop pipe to be positioned eccentric to the well casing and even if such glands do permit some adjustment of the drop pipe, the adjustment is not of a permanent character as is the structure herein disclosed.

What I claim is:

1. A combined well casing head forming and drop pipe clamping and supporting structure

comprising a tubular head member for snugly encompassing the casing having an enlarged upper portion provided with an annular seal receiving recess disposed coaxially with the casing, a cover plate mounted on such member and provided substantially at the center thereof with an opening of a diameter less than the diameter of the casing, means for securing said head and plate together, said opening being for the passage of the drop pipe into the casing, a drop pipe clamping and supporting device arranged over and horizontally adjustable, with the pipe clamped thereto relative to said cover plate selectively in opposite directions, and means carried by said device and engaging in said plate for fixedly securing said device selectively in non-adjusted and adjusted positions with the head member and with the drop pipe clamped to said device.

2. A combined well casing head forming and drop pipe clamping and supporting structure comprising a tubular head member for snugly encompassing the casing having an enlarged upper portion provided with an annular seal receiving recess disposed coaxially with the casing, a cover plate mounted on such member and provided substantially at the center thereof with an opening of a diameter less than the diameter of the casing, means for securing said head and plate together, said opening being for the passage of the drop pipe into the casing, a drop pipe clamping and supporting device, arranged over and horizontally adjustable, with the pipe clamped thereto relative to said cover plate selectively in opposite directions, and means carried by said device and engaging in said plate for fixedly securing said device selectively in non-adjusted and adjusted positions with the head member and with the drop pipe clamped to said device.

3. A combined well casing head forming and drop pipe clamping and supporting structure comprising a tubular head member for snugly encompassing the casing and having its upper end provided with an annular seal receiving recess disposed coaxially with the casing, a cover plate mounted on the upper end of said member and provided substantially at the center thereof with an opening of less diameter than the casing for the passage of the drop pipe into the casing, spaced means coacting with spaced parts of said member and plate for fixedly securing them together, an upstanding drop pipe clamping and supporting device arranged over and horizontally adjustable relative to said plate with the pipe clamped thereto, said device being formed at its upper end with an annular seal receiving recess arranged coaxially with the drop pipe, and spaced means coacting with external spaced parts at the lower end of said device and engaging in said plate for selectively securing said device in adjusted and non-adjusted positions with said head member and with the drop pipe clamped to said device.

CLAUSEY L. DAILEY. 65
